UNITED STATES PATENT OFFICE.

CHARLES R. HADLEY, OF LOS ANGELES, CALIFORNIA, ASSIGNOR TO CHARLES R. HADLEY COMPANY, OF LOS ANGELES, CALIFORNIA, A CORPORATION OF CALIFORNIA.

EXTENSION-COVER LOOSE-LEAF BINDER.

1,331,912.

Specification of Letters Patent. Patented Feb. 24, 1920.

Application filed May 12, 1917. Serial No. 168,142.

To all whom it may concern:

Be it known that I, CHARLES R. HADLEY, a citizen of the United States, residing at Los Angeles, in the county of Los Angeles and State of California, have invented a new and useful Extension-Cover Loose-Leaf Binder, of which the following is a specification.

This invention relates to devices of the character designed to detachably hold a series of leaves or sheets and also includes the leaves themselves.

More particularly the invention in some of its aspects relates to that type of binder in which the leaves may be offset from one another, the offsetting being employed to indicate the live or active accounts of any particular period of time, such offsetting being employed extensively for instance, in machine bookkeeping.

With binders of prior construction having a plurality of posts or pins rigidly connected to the cover members it has been necessary to make a perforation in each leaf for each post, thus entailing considerable time and labor in making the perforations and also waste of the paper. Besides this a large number of perforations is objectionable in machine bookkeeping, since the leaves are run through an adding machine and, owing to the large number of perforations, are apt to be torn when running through the machine.

An object of this device is to minimize the tendency to tearing of the leaves when they are run through an adding machine or the like.

Another object is to facilitate the fastening and unfastening of the leaves in the binder.

Another object is to produce a device of this character of which the leaves have their edges cut or indented to a minimum degree so that the leaves will pass through an adding machine or the like with little liability of becoming torn during the operation.

Other objects and advantages will appear in the subjoined detail description.

The accompanying drawings illustrate the invention:

Figure 1 is an elevation of the back of a binder constructed in accordance with this invention, leaves being shown in alinement with one another in the binder.

Fig. 2 is a sectional elevation of the binder in Fig. 1, some of the leaves being offset and the intermediate post being in its folded position.

Fig. 3 is a broken plan view of the lower cover of the binder in Figs. 1 and 2, the intermediate post being in the position shown in Fig. 2 and the end posts being swung out of their binding positions.

Fig. 4 is a sectional elevation on line indicated by x^4-x^4 , Fig. 1.

Fig. 5 is an enlarged sectional detail on line indicated by x^5-x^5 , Fig. 1.

Fig. 6 is a fragmentary plan view of one end of one of the binding strips showing the notch for receiving the post.

Fig. 7 is a reduced view of one of the leaves in Figs. 1 and 2.

There are provided covers respectively comprising binding strips 1, 2 and cover members 3, 4 hinged at 5, 6 to the respective binding strips. The binding strips 1, 2 may be of any suitable construction, but preferably as shown in the drawings, are rectangular tubes 7 having plugs inserted in their ends, the plugs for the binding strips 1 being indicated at 8 and those for the binding strip 2 being indicated at 9.

Pivoted at 10 in notches 11 of the plugs 9 are posts 12 which in the instance shown in the drawings are of sectional construction so that by providing different numbers of the sections the posts may be lengthened or shortened as desired so as to change the capacity of the binder. The notches 11 do not extend entirely through the plugs 9 so as to leave shoulders 13 adapted to prevent the posts 12 from swinging outward and downward beyond positions in planes substantially coinciding with the plane of the binding strip 2.

The plugs 8 are provided with notches 14 extending from side to side of the plugs and designed to accommodate the posts 12 when said posts are swung into their binding positions in Fig. 2. The notches 14 are counterbored at 15, the counterbores beginning in sufficiently far from the ends of the binding strip so as to leave shoulders 16 at the outer ends of the notches. The posts 12 are screw-threaded at 17 to receive nuts 18 which are provided with externally reduced portions 19 substantially fitting the notches 14 and which are provided with inclined faces 20

adjacent the reduced portions 19, said faces 20 fitting the counterbores 15. Thus when the posts are in the binding positions with the faces 20 of the nuts seated in the counterbores 15, the shoulders 16 will prevent the nuts from swinging away from the notches 14. The reduced portions 19 of the nuts protect the threads of the posts against contacting with the plugs 8 and consequently 10 prevent injury to said threads.

Between the covers of the binder are clamped, when the posts 12 are in binding position and the nuts 18 are in the counterbores 15, loose leaves 21, the edges of said 15 leaves resting against the posts and being held in alinement thereby. The clamping action of the posts 12 and nuts 18 holding the covers toward one another of itself would tend to hold the leaves 21 in place, 20 but if desired the leaves may be provided with notches 22, see Fig. 7, at opposite edges of each leaf, said notches fitting the posts so that when the posts are in the notches of the leaves the leaves cannot possibly be 25 displaced from their bound positions as in Fig. 2.

The binding strip 2 is provided with a recess or groove 23 and pivoted at 24 in said groove is a post 25, which may be 30 formed in sections as shown, said post being capable of being swung into vertical position relative to the binding strip as in Fig. 1 or into the groove 23 as in Figs. 2 and 3. When the leaves 21 are all in alinement with 35 one another and the post 25 is in binding position as in Fig. 1 said post fits into the notches 22 of the leaves so as to aid in retaining said leaves in their bound positions. Thus it is clear that when the leaves are 40 alined as in Fig. 1 they are held and alined at one edge by one of the end posts 12 and are held and alined at the other edge by the intermediate post 25.

From the foregoing it is seen that the post 45 25 is movable into and out of binding position.

When the intermediate post 25 is folded down into the groove 23 as in Fig. 2 some 50 of the leaves 21 may be offset from the others as said post will be out of the way of the leaves, and it is clear that some of the leaves are engaged and alined by one of the posts 12 and other of the leaves are engaged and alined by the other post 12.

55 When the post 25 is in its binding position as in Fig. 1 it passes through a perforation 26 in the binding strip 1.

In practice considering the binder parts 60 to be in the position shown in Fig. 1, if it be desired to take out or insert leaves in the binder, the nuts 18 will be turned to loosen them and then the posts 12 will be swung outward from the notches 14 thus releasing the binding strip 1. The cover 1, 3 will then 65 be removed and the desired number of sheets

removed or inserted and the cover may then be replaced by a reversal of the operations just noted.

When for any reason it is desired to offset some of the leaves 21 from others of the 70 leaves as, for example, to indicate which leaves have been run through an adding machine or the like, the leaves 21 will be raised sufficiently to allow the post 25 to be swung into the groove 23, whereupon any of the 75 leaves desired may be offset as shown in Fig. 2.

It is sometimes desirable to retain the leaves in their offset positions for an interval of time when the binder is closed and 80 in such event the cover 1, 3 will be placed in binding position and the posts 12 swung into binding positions just the same as described above when the leaves were in alinement with one another.

85 After checking up the accounts on the offset leaves, said leaves are once more alined with the other leaves and the post 25 will then be swung into binding position as in Fig. 1 so as to aid in retaining said 90 leaves.

I claim:

1. In combination, covers, one of said covers having a groove, means closable into the groove and movable therefrom to hold 95 leaves alined with one another nearer one edge of the covers than the opposite edge.

2. In combination, covers, a collapsibly mounted post positioned a substantial distance from the edges of the covers, said post 100 being movable into and out of binding position, and means independent of said post to hold the covers toward one another to clamp leaves therebetween.

3. In combination, covers, posts hinged to 105 one of the covers near its opposite edges, a third post hinged to one of the covers intermediate of the first named posts, the other of said covers having a perforation to receive the third post and having notches to 110 receive the end posts, and means to hold the end posts in said notches.

4. In combination, covers, posts hinged to one of the covers, there being notches in the other cover and said notches being counterbored, leaves between the covers having 115 notches closely fitting the posts, and nuts on the posts fitting into the counterbores when the posts are in the notches.

5. In combination, covers, leaves between 120 the covers having notches in their opposite edges, posts connected with the covers to fit the notches of different leaves when said leaves are offset from one another, and another post connected with one of the covers 125 to fit the notches at one edge of the leaves when the leaves are in alinement with one another.

6. In combination, covers, one of said covers having a groove, and the other cover 130

a perforation, means closable into the groove and movable therefrom and engageable with the perforation to engage leaves placed between the covers.

5 7. In combination, covers, leaves between the covers having notches in their opposite edges, means adapted to engage the notches when the leaves are in alinement with one another, and means coöperating with the

last-named means when one of the leaves is 10 offset from others of said leaves to engage one of the notches of the offset leaf.

Signed at Los Angeles, California, this
4th day of May 1917.

CHARLES R. HADLEY.
